UNITED STATES PATENT OFFICE.

WALTER R. KAHNS, OF CHICAGO, ILLINOIS, ASSIGNOR TO J. H. WHITE MFG. CO., OF BROOKLYN, NEW YORK, A CORPORATION OF NEW YORK.

COMBINED SHADE-HANGER AND LAMP-SOCKET SUPPORT FOR LIGHTING-FIXTURES.

1,122,763.

Specification of Letters Patent. Patented Dec. 29, 1914.

Application filed July 31, 1914. Serial No. 854,234.

To all whom it may concern:

Be it known that I, WALTER R. KAHNS, a citizen of the United States, residing at Chicago, in the county of Cook and State of Illinois, have invented an Improvement in Combined Shade-Hangers and Lamp-Socket Supports for Lighting-Fixtures, of which the following is a specification.

My invention relates to a hanger or hook 10 for suspending the shade, globe or bowls of lighting fixtures combined with a support for the sockets of incandescent electric lamps, particularly to that class of lighting fixtures for producing semi-indirect lighting effects, in which a transparent or translucent bowl is suspended, and the lead wires are brought to one or more lamp sockets within the bowl. In fixtures of this character it is customary to employ hangers or 20 hooks attached to the bowl, and to employ separate supporting arms or brackets for the lamp socket.

The object of my present invention is to provide a device in which the hook for suspending the bowl and the supporting arm for the lamp socket are made integral, thus dispensing with several parts heretofore necessary and at the same time facilitating the attachment of the hook and socket support to the bowl.

The details of the invention are hereinafter particularly described.

In the accompanying drawing:—Figure 1 is an elevation partially in section, illustrating my invention attached to a bowl. Fig. 2 is a perspective view of the same detached from the bowl. Fig. 3 is a plan view illustrating a blank from which the device may be formed. Fig. 4 is an elevation partially in section, illustrating a modification, and Fig. 5 is a plan view of such modified form.

Similar reference numerals indicate like parts throughout the several views.

45 10 indicates a bowl of transparent material, such as used in fixtures for producing a semi-indirect lighting effect.

11 indicates the hook or hanger portion of the device and 12 the socket supporting arm integral therewith. Intermediate these

parts 11 and 12 there is a somewhat widened portion which is provided with an opening 13.

Beneath the rim of the bowl 10 there is an opening 14 into which a headed bolt 15 fits. This bolt has a reduced screw-threaded end projecting within the bowl and through the opening 13 in the combined hanger and support, and a nut 16 screwed upon the screw-threaded end of the bolt 15 over the combined hanger and support secures the parts together. The end of the socket supporting arm 12 is provided with a circular opening 17.

18 indicates a hollow stud exteriorly 65 screw-threaded on its lower part. This stud 18 is secured at its upper part within the opening 17 on the end of the arm 12.

19 indicates a lamp socket screwed upon the screw-threaded lower end of the stud 18, 70 and 20 designates an incandescent electric lamp attached to said socket.

21 indicate the conductor wires which pass through the hollow stud and are looped through the links of the supporting chain 22. 75

My improved device is made of a single piece of brass or other metal stamped out as shown in Fig. 3, and sufficiently pliable to be bent into the shape shown in the drawings, or to such relative positions of the 80 combined parts as may be desired.

By the employment of my invention the hanging of the bowls and supporting the lamp sockets is greatly facilitated, the cost lessened, and several parts heretofore necessary are entirely dispensed with.

I claim as my invention:

1. A device for supporting an electric lamp socket and hanging a bowl in lighting fixtures, consisting of a horizontally extending metallic strip provided on one end with a screw threaded stud to receive a lamp socket and having at the other end an integral vertically extending portion, the upper end of which is bent back forming a hook to engage a chain, and means for attaching said device to a bowl. 90

2. In a lighting fixture, the combination of a bowl provided with a hole beneath its rim, a device for hanging said bowl and sup- 10

porting a lamp socket, consisting of a horizontally extending metallic strip provided on one end with a screw threaded stud, and having at the other end an integral vertically extending portion, the upper end of which is bent back forming a hook, there being an opening in said vertical portion of the strip, and means passing through said

opening and through the hole in said bowl for attaching said device to the bowl. 10
Signed by me this 23rd day of July 1914.

WALTER R. KAHNS.
